UNITED STATES PATENT OFFICE.

OLIVER H. HICKS, OF BALTIMORE, MARYLAND.

IMPROVEMENT IN MATCH-BOXES.

Specification forming part of Letters Patent No. 177,837, dated May 23, 1876; application filed March 23, 1876.

To all whom it may concern:

Be it known that I, OLIVER H. HICKS, of the city of Baltimore and State of Maryland, have invented certain new and useful Improvements in Match-Boxes, of which the following is a specification; and I do hereby declare that in the same is contained a full, clear, and exact description of my said invention, reference being had to the accompanying drawing, and to the letters of reference marked thereon.

My invention relates more especially to certain improvements in the striker, or that part of the match-box against which the matches are struck to ignite them, and in the arrangement of the striker with reference to the pockets or receptacles for the matches, as will hereinafter fully appear.

In the accompanying drawing, forming a part of this specification, Figure 1 is a front view of my improved match-box; Fig. 2, a transverse section of the same on line *x y*; and Fig. 3, a plan of the invention.

Similar letters of reference indicate similar parts in all the figures.

A are the pockets or receptacles for the matches, connected by the striker B, and with it secured to the back plate C, by means of rivets passing through lugs *a*, or they may be cast with the plate, in order that the entire match-box shall consist of a single piece. The striker B is a roughened plate, attached to and between the pockets A, in an inclined position with reference to the back plate, and with the greatest projection at the lower end. The upper end of the striker is preferably constructed to come into close contact with the back plate, so as to allow of the greatest possible angle with a given projection at the lower end.

By placing the striker in the inclined position described, less force is required to ignite the match, the friction being increased as the

match is drawn toward its lower edge. The ignited match is also brought sufficiently far from the wall to prevent its being discolored by smoke and flame, and the danger of the match passing from the striker to the wall, as it is brought over the lower edge, obviated.

The pockets A, being located on either side of the striker, serve to guide the match to the proper place for striking it—an advantage which will be readily appreciated by persons having occasion to use the match-box in the dark.

I do not claim an inward-inclined striker, nor an outward-inclined striker unless placed between vertical pockets, as shown, as my object is to not only provide a striker in the use of which the friction is greatly increased, but also to construct the box so that the two pockets A shall guide the match over the igniting-surface or striker.

The lower projection of the striker affords a convenient place below for a nail attachment of the box to the wall; and while both pockets may be used for the reception of matches, it is proposed also to use one pocket for holding the struck matches or stubs.

Having thus described my invention, what I claim as new, and wish to secure by Letters Patent of the United States, is—

As a new article of manufacture, a match-box having the back plate C, the vertical side pockets A, and the outward-inclined striker *c*, placed centrally between said pockets, constructed substantially as herein specified, and for the purposes described.

In testimony whereof I have hereunto subscribed my name this 1st day of March, in the year of our Lord, 1876.

OLIVER H. HICKS.
